IGNITING ELECTRODE ARRANGEMENT
AND METHOD

Laurence K. Marshall, Cambridge, Mass., assignor to Raytheon Manufacturing Company, Newton, Mass., a corporation of Delaware

Application February 21, 1939, Serial No. 257,645

15 Claims. (Cl. 250—27.5)

This invention relates to a novel igniting electrode arrangement for starting an arc spot on a pool type cathode. The igniting electrode is of the type which is separated by an insulating wall from the cathode, and initiates an arc by means of a high voltage impressed between the cathode and the igniting electrode. In devices of this kind, difficulties have been encountered in securing long life. After comparatively short periods of operation, voltages which initially would produce fairly reliable starting were no longer sufficient, and the starting became erratic. This effect became progressively worse until the practical life of the tube terminated.

An object of this invention is to devise a method of operating tubes having an arc-starting arrangement of the foregoing type, whereby long life is secured.

Another object is to devise an arrangement for carrying out the novel method.

A further object is to insure reliable starting during life.

A still further object is to prevent substantial change in the starting characteristics during life.

The foregoing and other objects of this invention will be best understood from the following description of an exemplification thereof, reference being had to the accompanying drawing, wherein the figure is a cross-section of a tube embodying the invention, together with a diagrammatic representation of a circuit with which said tube may be used.

The tube illustrated comprises a sealed envelope 1, a pool type cathode 2, preferably consisting of a pool of mercury, and an anode 3. In order to provide means for initiating an arc spot on the surface of the cathode pool 2, the tube is provided with an igniting electrode 4, consisting of a rod of conducting material sealed through the bottom wall of the envelope 1. The igniting electrode 4 is separated and insulated from the cathode pool 2 by means of an insulating layer 5 covering the surface of the igniting electrode 4. This insulating coating or layer is preferably made of glass sealed to the surface of said igniting electrode. The igniting electrode, together with its insulating coating, are preferably constructed in accordance with the co-pending application of Percy L. Spencer, Serial No. 251,069, filed January 16, 1939, in which the insulating layer 5 is described as having a thickness of the order of ten mils or less. However, it is to be understood that the present invention is not limited to this particular construction of igniter inasmuch as larger thicknesses of glass

could likewise be utilized. External electrical connection may be made to the cathode 2 through a pair of lead-in conductors 6—6 sealed through the lower wall of the envelope 1 and projecting into the pool 2. External electrical connection may also be made to the anode 3 through the anode lead-in 7 sealed through the upper end of the envelope 1. Inasmuch as the igniting electrode 4 is likewise sealed through the lower wall of the envelope 1, direct electrical connection may be made to it.

In tubes of the type described above, the application of a comparatively high voltage to the igniting electrode 4 will initiate a cathode spot 15 on the mercury pool 2, and the anode 3 will pick up and maintain said cathode spot if the voltage impressed on the anode 3 is positive. The initiation of the cathode spot occurs at the surface of the mercury pool 2 substantially where the insulating member 5 emerges from said surface. In prior arrangements it has been found that after a comparatively short period of operation, the starting of the arc spot became erratic and the tubes had a short operating life. I have found, 20 however, that this difficulty can be substantially eliminated by producing relative motion between the surface of the insulating member 5 and the surface of the mercury pool 2 at the point where the arc spot tends to form. As pointed out above, this consists of a region surrounding the circumference of the insulating member 5 as it emerges from the surface of the mercury pool 2. I have found that by producing such a motion, not only is the life of the tube lengthened but also the 25 tube is made more sensitive in that lower voltages applied to the igniting electrode 4 will produce reliable ignition of the arc spot.

In accordance with my present understanding of the theory of operation of these tubes, the 30 novel results described above are due substantially to the following reasons. I believe that the erratic behavior of the tubes and the termination of the life thereof are due to the contamination of the surface of the insulating member 5 at the 35 region where the arc spot tends to form. This contamination appears to be due, at least in part, to the accumulation of impurities on the surface of the mercury pool 2. If these impurities are permitted to come into intimate contact with the insulating member 5, under the action of the arc 40 these impurities attach themselves to the surface of the insulating member, and thus desensitize it. I believe that by producing the relative motion described above, these impurities are 45 washed away from the surface of the insulating member 5.

member 5, and are thus kept from coming into intimate contact with said insulating member. It may be possible that if small amounts of impurities are driven out from the insulating member 5 itself, such impurities likewise will be washed away from the insulating member which is thus maintained in a clean and sensitive condition. The mere mechanical motion of the mercury relative to the insulating member 5 likewise appears to increase the sensitivity of the device, enabling lower igniting voltages to be used.

The arrangement shown in the drawing illustrates one mode of producing the necessary relative motion. Around the insulating member 5 is disposed an elongated tubular member 8 which may be formed of any suitable material, such as, for example, a metal. This tube is open at its upper and lower ends so that mercury may freely circulate therethrough. The tube 8 may be conveniently supported by being welded at its lower end to the two cathode lead-in conductors 6-6. Surrounding the tube 8 is a plunger 9 made of magnetic material. The plunger 9 is provided with a central bore which fits fairly closely around the tube 8 but which permits the member 9 to slide freely along said tube. The outer circumference of the member 9 likewise is designed to fit closely within the lower extension 10 formed on the sealed envelope 1. A slight clearance is left between the inner walls of the extension 10 and the outer diameter of the plunger 9 in order that the plunger 9 may slide freely within said extension 10. The clearances between the plunger 9, the extension 10, and the tube 8 are made sufficiently small, however, so that mercury cannot flow freely through the intervening spaces. The plunger 9 is provided with one or more bores 11 extending through the plunger 9, each of said bores terminating in an upper opening 12 of somewhat smaller diameter than the corresponding bore 11. In each of the bores 11 is placed a ball 13 which may be made of some suitable material, such as, for example, steel. In order to prevent the balls 13 from being pushed out of the bores 11, a strip 14 may be welded across the lower end of each bore 11. Of course it is to be understood that the width of each strip 14 is considerably less than the lower opening in the bore 11, so that a free flow of mercury through said opening is permitted. In order to bias the plunger 9 to its proper position, a coil spring 15 is interposed between the lower face of said plunger 9 and the lower wall of the envelope 1. If the plunger 9 is made of a material which has a tendency to float, the coil spring 15 should be anchored to the lower wall of the envelope 1 and also to the lower surface of the plunger 9. In order to actuate the plunger 9, the extension 10 of the envelope 1 is surrounded by an actuating coil 16 fed from a source of pulsating current 17. The coil 16 is disposed somewhat below the deenergized position of the plunger 9.

When the coil 16 is supplied with a pulse of current from the source 17, the plunger 9 is pulled down by the magnetic field created in the coil 16. The balls 13 close the opening 12, and thus mercury is trapped between the lower surface of the plunger 9 and the lower wall of the envelope 1. The mercury so trapped is therefore pushed up through the tube 8, as indicated by the arrows therein, and ejected through the opening in the top of the tube 8. Upon the cessation of said current pulse, the coil 16 is de-

energized and the plunger 9 moves upwardly, due to the pressure exerted by the spring 15 which previously had been compressed upon the downward motion of said plunger. Upon said upward motion, the balls 13 are pushed away from the openings 12 and the mercury above the plunger 9 can flow freely through said openings to the lower portion of the extension 10. Subsequent pulses of current supplied to the coil 16 produce additional pulses of mercury flow up through the tube 8. The pumping action described produces a flow of mercury around the insulating member 5 at the point where said insulating member emerges from the surface of the pool 2. This relative motion produces the various novel results which I have described above.

The tube illustrated may be utilized in a large number of circuits, one of which is shown diagrammatically. This circuit consists of a power transformer 18 having a primary winding 19 connected to a suitable source of alternating current, and a secondary winding 20. One end of the secondary winding is connected to the lead-in 7 and thus to the anode 3, while the other end of said secondary winding is connected through a load 21 to the two cathode leads 6-6 which are connected together. An igniting voltage may be impressed between the igniting electrode 4 and the cathode pool 2 from an igniting voltage control 22 which is energized through conductors 23-23, preferably from the same alternating current source as that which supplies the primary winding 19. By supplying igniting impulses of proper phase to the igniting electrode 4, an arc is initiated during each positive voltage swing of the main anode 3, and thus a controlled discharge current passes between the cathode 2 and the anode 3, which current is in turn delivered to the load 21.

Of course it is to be understood that this invention is not limited to the particular arrangement as described above inasmuch as many equivalents will suggest themselves to those skilled in the art. Various other forms of igniting electrode structure, which are immersed in the cathode pool and project through its surface, could be used and various other modes of producing relative motion between the mercury and the igniting electrode structure could likewise be devised. It is accordingly desired that the appended claims be given a broad interpretation commensurate with the scope of the invention within the art.

55. What is claimed is:

1. The method of operating an arc discharge device of the type having a liquid pool cathode, and igniting means of the electrostatic type comprising an electrode adjacent the surface of said cathode and separated therefrom by an insulating wall, which comprises producing relative motion between the cathode liquid and said insulating wall at the surface of said cathode in a direction substantially parallel with the surface of said insulating wall during the passage of the discharge from said cathode.

2. The method of operating an arc discharge device of the type having a liquid pool cathode, and igniting means of the electrostatic type comprising an electrode adjacent the surface of said cathode and separated therefrom by an insulating wall, which comprises producing relative motion between the cathode liquid and said insulating wall at the surface of said cathode in a direction substantially parallel with the surface

of said insulating wall throughout the operation of said device.

3. The method of operating an arc discharge device of the type having a liquid pool cathode, and igniting means of the electrostatic type comprising an electrode adjacent the surface of said cathode and separated therefrom by an insulating wall which comprises moving the cathode liquid relative to said insulating wall at the surface of said cathode in a direction substantially parallel with the surface of said insulating wall during the passage of the discharge from said cathode.

4. An arc discharge device comprising an anode, a liquid pool cathode, and igniting means of the electrostatic type comprising an electrode adjacent the surface of said cathode and separated therefrom by an insulating wall, and means for producing relative motion between the cathode liquid and said insulating wall at the surface of said cathode in a direction substantially parallel with the surface of said insulating wall during the passage of the discharge from said cathode.

5. An arc discharge device comprising an anode, a liquid pool cathode, and igniting means of the electrostatic type comprising an electrode adjacent the surface of said cathode and separated therefrom by an insulating wall, and liquid pumping means for moving the cathode liquid relative to said insulating wall at the surface of said cathode.

6. An arc discharge device comprising an anode, a liquid pool cathode, and igniting means of the electrostatic type comprising an electrode adjacent the surface of said cathode and separated therefrom by an insulating wall, and pumping means for moving the cathode liquid relative to said insulating wall at the surface of said cathode.

7. The method of operating an arc discharge device of the type having a liquid pool cathode, and igniting means of the electrostatic type comprising an electrode structure immersed in said pool and projecting through its surface, which comprises producing relative motion between the cathode liquid and said igniting electrode structure at the surface of said cathode in a direction substantially parallel with the surface of said igniting electrode during the passage of the discharge from said cathode.

8. The method of operating an arc discharge device of the type having a liquid pool cathode, and igniting means of the electrostatic type comprising an electrode structure immersed in said pool and projecting through its surface, which comprises moving the cathode liquid relative to said igniting electrode structure at the surface of said cathode in a direction substantially parallel with the surface of said igniting electrode during the passage of the discharge from said cathode.

9. An arc discharge device comprising an anode, a liquid pool cathode, and igniting means of the electrostatic type comprising an electrode

6 structure immersed in said pool and projecting through its surface, and means for producing relative motion between the cathode liquid and said igniting electrode structure at the surface of said cathode in a direction substantially parallel with the surface of said igniting electrode during the passage of the discharge from said cathode.

10. The method of operating an arc discharge device of the type having a liquid pool cathode, and igniting means of the electrostatic type comprising an electrode adjacent the surface of said cathode and separated therefrom by an insulating wall, which comprises producing relative motion between the cathode liquid and said insulating wall at the surface of said cathode in a direction substantially parallel with the surface of said insulating wall.

11. The method of operating an arc discharge device of the type having a liquid pool cathode, and igniting means of the electrostatic type comprising an electrode adjacent the surface of said cathode and separated therefrom by an insulating wall which comprises moving the cathode liquid relative to said insulating wall at the surface of said cathode in a direction substantially parallel with the surface of said insulating wall.

12. An arc discharge device comprising an anode, a liquid pool cathode, and igniting means of the electrostatic type comprising an electrode adjacent the surface of said cathode and separated therefrom by an insulating wall, and means for producing relative motion between the cathode liquid and said insulating wall at the surface of said cathode in a direction substantially parallel with the surface of said insulating wall.

13. The method of operating an arc discharge device of the type having a liquid pool cathode, 40 and an igniting electrode structure immersed in said pool and projecting through its surface, which comprises producing relative motion between the cathode liquid and said igniting electrode structure at the surface of said cathode 45 in a direction substantially parallel with the surface of said igniting electrode structure.

14. The method of operating an arc discharge device of the type having a liquid pool cathode, and an igniting electrode structure immersed in said pool and projecting through its surface, which comprises moving the cathode liquid relative to said igniting electrode structure at the surface of said cathode in a direction substantially parallel with the surface of said igniting electrode.

15. An arc discharge device comprising an anode, a liquid pool cathode, and an igniting electrode structure immersed in said pool and projecting through its surface, and means for producing relative motion between the cathode liquid and said igniting electrode structure at the surface of said cathode in a direction substantially parallel with the surface of said igniting electrode structure.
